PADLOCK

Charles E. Olson, Bridgeport, Conn.

Application August 22, 1942, Serial No. 455,695

12 Claims. (Cl. 70—51)

This invention relates to padlocks and to attachments therefor for preventing water and dirt from accumulating in and about the apertures in the body of the lock and the portions of the legs of the shackle which extend into the same.

In the use of padlocks outdoors, particularly in the colder climates, it frequently happens that when the lock is to be opened it is found that water, which has accumulated in and about the shackle-receiving apertures and the legs of the shackle, has frozen, and that the lock cannot be opened until the ice has been melted. It has also been found, especially with the type of padlock in which the free end of the shackle extends into a blind hole, that the accumulation of dirt and other foreign matter in this hole prevents the shackle from being moved to locked position, and this necessitates cleaning out the blind hole with a screw driver or the like.

To avoid these troubles and inconveniences, the present invention provides resilient shields on the legs of the lock shackle so positioned that when the shackle is closed the end of the shields will firmly engage and make watertight contact with the margins of the apertures in the body of the lock through which the legs extend.

These resilient shields, according to this invention in the form at present preferred, are in the form of collars of rubber or rubber-like material carried by the legs of the shackle and positioned thereon so that the ends of the collars adjacent the body of the lock will be held under pressure against the margins of the leg-receiving apertures and thus maintain watertight contact with the body of the lock.

According to the present invention, the rubber collar may be provided with an undersize axial hole through which the leg of the shackle may be threaded so that the collar will embrace the leg of the shackle resiliently with sufficient firmness to prevent casual or operational displacement of the collar from adjusted position on the leg of the shackle.

Preferably, the body-engaging end of the collar is made quite flexible, as by reducing its cross-sectional area, so that it will yield more readily than the other end which grips the shackle leg. At present, it is preferred to do this by providing an enlarged bore in the collar at the body-engaging end, since this produces a flexible skirt portion which is spaced from the shackle leg and which may be bowed outwardly upon engagement with the body as the shackle is being closed and spring back somewhat while maintaining firm contact with the body as the shackle

moves outward slightly after being caught by the lock mechanism.

The provision of the skirt portion on the rubber collar is advantageous also for the reason that should there be a coating or accumulation of ice at the point of engagement of the rubber collar with the lock body, this may usually be cracked and broken with comparative ease by manually applying pressure on the skirt portion of the shield causing it to flex inwardly and permitting the ice to crack. Thus it is unnecessary to chip the ice away as would be required in case this relative movement between the skirt portion, the leg and the body were not permitted.

The shields of the present invention may be permanently secured on the legs of the shackle by the manufacturer of the lock, or they may be provided as an attachment to existing locks. When desired, especially when the shackle of the lock to which the shields of the present invention are to be applied is of unusually small cross-section, they may be secured in place against casual or operational displacement by a suitable adhesive, such as shellac.

With most locks, it is the better practice to provide the shield of the present invention on both legs of the shackle, but in other locks this may not be necessary, and it should be understood that the shield of the present invention may be applied to either or both legs of the shackle as desired.

It should be understood that in the specification and claims the word "rubber" is used as a convenient term intended to embrace all rubber, rubber substitutes, and rubber-like materials.

Other features and advantages will herein-after appear.

In the accompanying drawing:

Fig. 1 is a front elevation of a padlock showing the shields of the present invention applied to the legs of the shackle, the shackle being shown in unlocked position.

Fig. 2 is a similar view showing the shackle in locked position.

Fig. 3 is a horizontal sectional view taken through the bowed skirt portion of the device.

Fig. 4 is an elevation of the shield of the present invention.

The padlock shown herein to illustrate the present invention comprises a body 10 and a shackle 11 having legs 12 and 13. The shackle is movable longitudinally from the open or unlocked position shown in Fig. 1 to the closed or locked position shown in Fig. 2, the legs of the

shackles being slidably mounted in apertures 14 in the body of the lock. In some instances, the shackle moves sufficiently far beyond the end of the body 10 to permit a hasp or other means to be caught by the shackle to pass between the end of the leg 13 and the body. In other instances, the lock is so constructed that the shackle pivots about the leg 12 to permit access to the loop of the shackle.

The legs of the shackle have notches 15 adapted to be engaged by keepers 16 diagrammatically shown in dotted lines in Fig. 2 which are moved from operative to inoperative positions by a key-controlled tumbler mechanism 17 also diagrammatically illustrated in dotted lines in Fig. 2. Due to lost motion in the lock parts, particularly between the keepers 16 and the notches 15, it is usual in padlocks that when the shackle is pressed home to be caught it is capable of some slight outward movement, and usually does have such movement under the influence of a spring not shown which causes the shackle to move out automatically when the lock is unlocked.

In the use of padlocks, particularly outdoors in colder climates, it frequently occurs that ice forms in and about the leg-receiving apertures 14 and the adjacent portions of the legs due to an accumulation of rain freezing therein or due to sleet or snow. This formation of ice interferes with the operation of the lock, and many times prevents the lock from being opened until the ice has been melted either naturally or artificially as by a blowtorch. This causes a great deal of inconvenience and trouble. In some padlocks, the free leg 13 of the shackle enters into a blind hole in the body which is liable to become clogged with dirt or other foreign matter so that the shackle cannot be pushed home sufficiently far to be caught by the keeper until the accumulation has been removed by means of a screw driver or other pointed instrument.

The device of the present invention obviates the difficulties above referred to not only by preventing water from entering in and about the shackle-receiving apertures in the body but also preventing dirt from entering the lock through these apertures.

In the form of the invention illustrated herein as exemplary thereof, this is accomplished by providing on either or both legs of the shackle, depending upon the construction of the lock, resilient shields 18. These shields preferably are in the form of cylindrical resilient rubber collars having an axial hole 19 through which the legs 13 and 12 of the shackle may be threaded.

In the example shown in the accompanying drawing, the collar for the leg 12 is first placed on the leg 13 and then pushed around the loop of the shackle until it is brought to position on the leg 12 and the collar for the leg 13 is pushed onto that leg. The hole 19 is preferably undersize (considering the diameter of the shackle legs) so that the collar will be under slight resilient distortion and thus be firmly gripped onto the shackle leg to be held in adjusted position against casual or operational displacement. If it is desired to permanently secure the collar 18 in adjusted position on the shackle, especially in cases where the shackle is of unusual small cross-section, this may be done by the use of suitable adhesive such as shellac.

The collar 18 is located on the leg of the shackle in such position that its lower end encircles and firmly engages the margin 20 of the leg-receiving apertures 14 when the lock is closed to

form a watertight connection around the aperture 14. To improve the making of this watertight connection I have found that the body-engaging end of the collar may advantageously be made as a resilient skirt 21. This may be done by providing an enlarged bore 22 in the collar, preferably tapered, so that the skirt 21 becomes more flexible toward its bottom and is spaced from the portion of the leg which it surrounds. When the collars are so made and are properly adjusted on the legs of the shackle, movement of the shackle from open position shown in Fig. 1 to closed position shown in Fig. 2 causes the skirt to bow outwardly and be placed under pressure so that its end firmly engages the margin 20 of the aperture 14. When the shackle is manually released so that it may move outwardly until the keepers 16 engage the notches 15, the bow in the skirt 21 straightens out slightly but continues to maintain close waterproof contact with the body of the lock.

The flexible skirt 21 has the further advantage that it permits relative movement between itself and the leg of the shackle, and this greatly assists the breaking and cracking of a layer of ice which may accumulate around the collar and adjacent parts of the lock body. This could not be done with such ease if the body-engaging end of the collar snugly embraced the portion of the shackle which it surrounds.

Variations and modifications may be made within the scope of this invention and portions of the improvements may be used without others.

I claim:

1. A padlock having a body; a shackle having legs slidably mounted in apertures in the body to open and close the lock; and resilient means encircling the legs of the shackle and carried thereby in position to engage the margins of said apertures and be placed under pressure thereagainst when the shackle is moved to closed position, the portion of the resilient means engaging the margin being deformable to form a seal therearound and prevent foreign matter from settling in and about said apertures and the portions of the legs entering the same.
2. A padlock having a body; a shackle having legs slidably mounted in apertures in the body to open and close the lock; and resilient means encircling the legs of the shackle and carried thereby in position to engage the margins of said apertures and be placed under pressure thereagainst when the shackle is moved to closed position, the portion of the resilient means engaging the margin being deformable to form a seal therearound and prevent foreign matter from settling in and about said apertures and the portions of the legs entering the same, said resilient means being adjustably mounted on the legs of the shackle.
3. A padlock having a body; a shackle having a leg slidably mounted in an aperture in the body to open and close the lock; and a rubber collar encircling said leg of the shackle and resiliently embracing the same to maintain a desired adjusted position on the leg, said rubber collar having a compressible end portion positioned to engage the margin of the aperture and be placed under pressure theréagainst when the shackle is moved to closed position, said compressible end portion deforming and forming a seal to prevent water from settling in and about said aperture and the portion of the leg entering the same.
4. A padlock having a body; a lock mechanism; a shackle having a leg slidably mounted in an

aperture in the body to open and close the lock; and a rubber collar encircling said leg of the shackle and resiliently embracing the same to maintain a desired adjusted position on the leg, said rubber collar having an end portion positioned to engage the margin of the aperture and be placed under pressure thereagainst when the shackle is moved to closed position to prevent water from settling in and about said aperture and the portion of the leg entering the same, the body-engaging end of the collar having a reduced cross-section to provide a flexible skirt portion adapted to resiliently maintain watertight contact with the body after the shackle moves outwardly slightly after being caught by the lock mechanism.

5. A padlock having a body; a shackle having a leg slidably mounted in an aperture in the body to open and close the lock; and a rubber collar encircling said leg of the shackle and resiliently embracing the same to maintain a desired adjusted position on the leg, said rubber collar having an end portion positioned to engage the margin of the aperture and be placed under pressure thereagainst when the shackle is moved to closed position to prevent water from settling in and about said aperture and the portion of the leg entering the same, the body-engaging end of the collar being recessed to provide a flexible skirt portion spaced from the shackle leg so that it may be manually flexed to break any coating or accumulation of ice that may be formed over the collar and adjacent portions of the body.

6. A padlock having a body; a shackle having a leg slidably mounted in an aperture in the body to open and close the lock; and a rubber collar encircling said leg of the shackle and having at least a portion thereof which is readily compressible and deformable, the collar being positioned thereon so that an end portion engages the margin of the aperture and is placed under pressure thereagainst when the shackle is moved to closed position to cause the compressible portion to form a seal thereabout and to prevent water from settling in and about said aperture and the portion of the leg entering the same.

7. A padlock having a body; a lock mechanism; a shackle having a leg slidably mounted in an aperture in the body to open and close the lock; and a rubber collar encircling said leg of the shackle and positioned thereon so that an end portion engages the margin of the aperture and is placed under pressure thereagainst when the shackle is moved to closed position to prevent water from settling in and about said aperture and the portion of the leg entering the same, the body-engaging end of the collar having a flexible skirt adapted to resiliently maintain watertight contact with the body after the shackle moves outwardly slightly after being caught by the lock mechanism.

8. A padlock having a body; a shackle having a leg slidably mounted in an aperture in the body to open and close the lock; and a rubber collar encircling said leg of the shackle and positioned thereon so that an end portion engages the margin of the aperture and is placed under pressure thereagainst when the shackle is moved to closed position to prevent water from settling in and about said aperture and the portion of the leg entering 70

the same, the body-engaging end of the collar having a flexible skirt spaced from the shackle leg so that it may be manually flexed to break any coating or accumulation of ice that may be formed over the collar and adjacent portions of the body.

9. A padlock having a body; a lock mechanism; a shackle having legs slidably mounted in apertures in the body to open and close the lock; and rubber collars encircling the legs of the shackle and positioned thereon, said collars having end portions which are more compressible than the body thereof, said end portions engaging the margins of the apertures and being compressed and placed under pressure thereagainst to form a seal therearound when the shackle is moved to closed position to prevent water from settling in and about said apertures and the portions of the legs entering the same.

20 10. A padlock having a body; a lock mechanism; a shackle having legs slidably mounted in apertures in the body to open and close the lock; and rubber collars encircling the legs of the shackle and positioned thereon so that end portions engage the margins of the apertures and are placed under pressure thereagainst when the shackle is moved to closed position to prevent water from settling in and about said apertures and the portions of the legs entering the same,

25 30 the body-engaging ends of the collars each having a bore providing a flexible skirt portion adapted to bow when engaged with the body portion and maintain a watertight contact therewith when the shackle moves outwardly slightly due to lost motion between it and the lock mechanism.

35

mechanism.

11. An attachment for a padlock having a shackle forming legs slidably mounted in apertures in a lock-body to open and close the lock, comprising resilient means having a hole there-through through which one leg of the shackle may be passed to position said means thereon so that an end portion may engage the margin of one aperture in the body of the lock when the lock is closed, said body-engaging end portion having a flexible skirt spaced from the surface of the shackle leg and adapted to be placed under pressure to prevent water from settling in and about said aperture and the portion of the leg entering the same when the shackle is moved to closed position.

55 12. An attachment for a padlock having a shackle forming legs slidably mounted in apertures in a lock-body to open and close the lock comprising a collar of rubber having an axial hole through which one leg of the shackle may be pushed, said hole being undersize so that the collar resiliently embraces the shackle leg and thereby remains against casual or operational displacement in adjusted position on the leg with the end of the collar positioned to engage the margin of one aperture in the body of the lock when the lock is closed, said body-engaging end portion having a bore larger than said hole portion and a skirt spaced from the shackle leg and adapted to flex and maintain watertight contact with the body when the shackle is moved to closed position.

CHARLES E. OLSON,
